United States Patent Office

Des. 219,709
Patented Jan. 12, 1971

219,709

PLAQUE

Robert McDonald, Yardley, Pa., assignor to The Hibbert Company, Trenton, N.J., a corporation of New Jersey

Filed Jan. 21, 1970, Ser. No. 21,025

Term of patent 14 years

Int. Cl. D11—99

U.S. Cl. D29—23

FIG. 1 is a front elevational view of a plaque showing my new design; and

FIG. 2 is an edge view thereof shown broken away for convenience of illustration.

I claim:

The ornamental design for a plaque, as shown and described.
